To all whom it may concern:

Be it known that I, Michael E. Gluhareff, a citizen of the United States, residing at Bridgeport, county of Fairfield, State of Connecticut, have invented a new, original, and ornamental Design for a Helicopter, of which the following is a specification, reference being had to the accompanying drawings, forming a part thereof.

Fig. 1 is a top plan view of a helicopter, showing my new design;

Fig. 2 is a side elevational view;

Fig. 3 is a front elevational view;

Fig. 4 is a perspective view.

Certain of the rotor blades have been shown only partially due to space limitations because they are identical with those shown in full.

I claim:

The ornamental design for a helicopter, substantially as shown.
